SIGNALING DEVICE AND ATTACHMENT
THEREFOR

William Zenchenko, Park Falls, Wis.

Application February 18, 1957, Serial No. 640,963

4 Claims. (Cl. 116—67)

The present invention relates generally to improvements in the art of signaling devices, and particularly to signaling devices and attachments adapted for and used with vessels of the type in which food and drink are served to direct attention to the fact that the vessel has attained a condition which its possessor desires altered.

In the purchase and consumption of food and drink in restaurants and public houses, service, such as that provided by waitresses, is usually not limited to one's self. Accordingly, it is frequently necessary to call one's waitress to the table while she is momentarily distracted by her other chores. The problem of gaining such a servant's attention, such as during busy times, can be vexatious and, indeed, frustrating if it is to be achieved in a dignified and orderly manner. The technique of "catching" her eye is likely to be more unsuccessful than not, while whistling and shouting are definitely frowned upon in more polite circles. Accordingly, a very definite need exists whereby one who is either eating or drinking or both may summon his waitress or the like in an orderly, dignified and successful manner and eliminate the frustrations of being ignored.

Means have heretofore been proposed for solving this problem, such as the beer stein having a bell clapper suspended from and within its base. However, this stein and such similar proposals suffer the disadvantage that the signal is integrally formed with a specific serving unit and unless that specific unit is used, the signal is useless.

Another, though somewhat secondary, disadvantage of these devices is that their signaling devices were concealed from view with sham bases and, therefore, added nothing to the good humor of what should otherwise be a pleasant occasion.

A second problem arising from the situation described above is that sweating of the vessel and sometimes spillage of the contents from the vessel can not be avoided. When these events occur, damage is sometimes inflicted upon the serving surface and the customer's clothing, and always it is annoying.

In response to this problem the coaster art has been fairly well developed and, insofar as the solution of this single problem is concerned, appears fairly adequate.

When these two problems are considered jointly (and in practice one rarely occurs without the other), no prior art is known which offers an adequate solution in a single assembly. Such a solution is now available and is the substance of the present invention.

Accordingly, a primary object of the present invention is to provide a unique and attractive signaling device of the type indicated with which the possessor of a vessel may, in a dignified and orderly manner, indicate that the contents of his vessel have been consumed.

Another important object of the present invention is to provide a unique signaling attachment of the type indicated by which the annoying and sometimes harmful effect of spillage or sweating of the vessel upon its serving surface and its user's clothing is significantly reduced, if not substantially eliminated.

2

Another object of the present invention is to provide a unique signaling attachment which cooperatively contacts with any standard vessel of the type in which food and drink are normally served to produce an audible signal whereby the user's waitress, bartender or the like, can be informed that the user of the vessel desires to be re-served.

Another object of the present invention is to provide a unique signaling attachment of simple manufacture, pleasing decor and of unitary assembly which is readily coactable and can be easily interchanged with the conventional vessels of the type in which food and drink are normally served to provide a signaling device which the possessor can operate at will to direct attention to himself.

These and still further objects are fulfilled by the present invention in a manner which becomes apparent from a consideration of the following detailed description of exemplary embodiments of the present invention in connection with the accompanying drawing in which like elements bear like number throughout the several views, and:

Fig. 1 is a vertical elevation, partially in section of one embodiment of the present invention;

Fig. 2 is a vertical elevation, partially in section of an embodiment of the present invention showing a modified base structure;

Fig. 3 is a vertical elevation of the present invention showing another base structure; and

Fig. 4 is a vertical section of another embodiment of the present invention.

Referring now to the drawing, the device of the present invention comprises a base member 10, a supporting member 11, and a resilient member 12 integral with and extending upwardly from supporting member 11. At the end of resilient member 12, remote of supporting member 11, is a hammer 13.

Considering the embodiment of Fig. 1, base member 10 comprises a plate 14 of any suitable geometric configuration normally used in coaster manufacture, having an internal channel 15 defined therein. Supporting member 11 cooperates with base member 10 to stabilize device by the slideable engagement of supporting member 11 in channel 15. Plate 14 may be made of any suitable material, such as paper, plastic, wood etc., which will cushion the vessel and absorb or catch moisture.

An optional base member 10', shown in Fig. 2, comprises a channel 15' defined on an external surface of plate 14. When in use, plate 14 is so disposed that channel 15' opposes countertop 16 or other serving surface and supporting member 11 is interposed therebetween. While in this embodiment vessel 17 is generally sufficient to stabilize the device, it is preferable that plate be of more dense material and/or massive material so that the assembly is stable whether vessel 17 rests upon base member 10' or not.

Another base member structure 10' is illustrated in Fig. 3 and comprises a dish having a bottom 18 upon which an upwardly extending flange 19 is peripherally disposed, and a resilient member 12, integrally secured thereto. This embodiment is particularly desirable for use in humid climates where the condensation resulting from cold drinks might otherwise mark or harm the serving surface.

It is contemplated that one skilled in the art may envisage other equivalents to effect the function of the various base members herein described, and it is intended that such equivalents are within the scope of the present invention, the present embodiments being merely exemplary of the present invention.

Supporting member 11 may be of any suitable configuration consistent with the objectives herein expressed

and of any suitable material although it is preferred that the material provide suitable rigidity to enable the supporting member to perform its described function.

Resilient member 12 is of any suitable elastic material, such as spring steel, rubber and the like, and may be formed integrally with or secured to supporting member 11 to provide a quasi-fulcrum at this intersection. A leaf spring 12 is shown in connection with Figs. 1, 2 and 3, while a coil spring 12' is shown in Fig. 4.

Hammer 13 likewise may be of any suitable firm material, such as hard rubber, glass, plastic, or the like, although it is preferred that the hammer be such that in colliding with the vessel that it provide an audible sound, but will not result in the breakage of either itself or the vessel for obvious safety reasons.

It is intended that hammer 13 be of any conventional or novel configuration such as might be suitable to the character of the establishment in which the device shall be used. It is possible that manufacturing concerns may desire to reproduce in plastic certain of their advertising symbols as the hammer of the device. Exemplary of the variations adaptable to this combination are a hatchet head, shown in Figs. 1 and 2 and indicated by the reference numeral 13, and a spheroid, shown in Figs. 3 and 4 and indicated by the reference numeral 13'.

It is understood, within the purview of the present invention, that hammer 13 and resilient member 12 may be integrally formed if desired. Furthermore, hammer 13 may be disposed in abutting, rather than spaced (as shown in the several views), relationship to vessel 17 for an elastic return to its abutting position after being drawn back and released by the vessel's user. This last mentioned embodiment, while suitable for certain uses, is not preferred for general barroom use because the self-damping action of the hammer prevents transmission of a vibrant and resonant signal.

A still further modification of the embodiments illustrated can be effected by defining hammer 13 in the geometric shape of a hollow solid and disposing seeds or pebbles and the like therein to effect a rattle when the hammer has been placed in motion.

In operation, for example, in a public house, the customer who has emptied his glass needs only to draw back on hammer 13 and release it. The cooperative action between resilient member 12 and base member 10 through supporting member 11 causes hammer 13 to spring forward to contact the empty glass 17 to produce an audible sound which informs the bartender that the customer desires his glass refilled.

While particular embodiments of the present inven-

tion are herein described and illustrated, it is understood that they are done so to exemplify the present invention and not to limit it. Rather, such modifications or adaptations, as would readily occur to one skilled in the art to which the present invention pertains, are intended to be equally contained within its scope, the present invention being limited only by the appended claims.

What is claimed is:

1. A signaling device comprising: a thin flat base member; a portable vessel of the type which when struck will emit sound independent of and coacting with said base member to maintain said base member substantially stationary relative to said vessel; a hammer member; and a resilient member operatively interposed between and cooperatively coacting with said base member and said hammer member to provide elastic movement of said hammer member relative to said base member and said vessel, said hammer member striking said vessel to provide an audible signal.
- 10 2. A signaling device according to claim 1 in which said thin base member has an upper and lower planar surface, said upper surface supporting an upwardly extending flange peripherally disposed thereupon and secured thereto.
- 15 3. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 20 4. A signaling device comprising: a thin plate member having an upper and a lower planar surface and an elongated channel defined therein intermediate said surfaces; a portable flat bottomed vessel supportable upon said upper planar surface and coactable therewith to maintain said plate member substantially stationary relative to said vessel; a hammer member; and a resilient member connecting said hammer member and said base member, said resilient member having a portion removably insertable within said channel for supporting said hammer member for oscillation relative to said plate member into and out of engagement with said vessel.
- 25 5. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 30 6. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 35 7. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 40 8. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 45 9. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
- 50 10. The combination comprising a thin flat base member, a resilient arm member secured to said base member and extending outwardly and upwardly therefrom and oscillatable in response to an external force applied thereto, and a hammer member integrally formed with and supported by said arm member and oscillatable therewith.
